E. R. FIELD

VACUUM CLEANER

Filed March 5, 1921

UNITED STATES PATENT OFFICE.

EGBERT R. FIELD, OF DETROIT, MICHIGAN, ASSIGNOR TO EUREKA VACUUM CLEANER COMPANY, OF DETROIT, MICHIGAN, A CORPORATION OF MICHIGAN.

VACUUM CLEANER.

Application filed March 5, 1921. Serial No. 449,779.

To all whom it may concern:

Be it known that I, EGBERT R. FIELD, a citizen of the United States of America, residing at Detroit, in the county of Wayne and State of Michigan, have invented certain new and useful Improvements in Vacuum Cleaners, of which the following is a specification, reference being had therein to the accompanying drawings.

10 The invention relates to vacuum cleaning apparatus and refers more particularly to the portable type which is provided with a swinging handle and with a suction tool directly connected to the fan casing.

15 The objects of my invention reside in the provision of a simple form of lock for retaining the handle in its different positions of rotative adjustment; in the formation of the inner or pivotal end of the handle of 20 soft light metal and the provision of a wear plate upon the inner end of the handle for engagement with the locking latch whereby wear upon the inner end of the handle is avoided.

25 The invention has for other objects the novel features of construction and combinations and arrangements of parts as more fully hereinafter set forth.

In the drawings:

30 Figure 1 is a side elevation of a vacuum cleaner embodying my invention;

Figure 2 is a bottom plan view thereof;

Figure 3 is a perspective view of the locking end of the handle;

35 Figure 4 is a cross section on the line 4-4 of Figure 3.

The vacuum cleaner has the motor casing 1, the fan casing 2, and the suction tool 3, and is supported by the rolls 4 at opposite ends of the suction tool, and the caster wheel 5 at the rear end of the motor casing 1.

40 For moving the vacuum cleaner over the floor it is provided with the handle 6 which 45 also supports the dust bag (not shown) connected to the tangential outlet opening of the fan casing 2. Ordinarily, the rotative position of the handle relative to the vacuum cleaner varies when the latter is in use upon 50 the floor; but when the vacuum cleaner is not in use, it is desirable to retain the handle in substantially vertical position. Also, when the vacuum cleaner is being used in

raised position, it is desirable to retain the handle in substantially horizontal position. 55

For securing the handle 6 in its substantially vertical and horizontal positions, one of the furcations 10' of the handle has the head 14, the end face of which is notched as at 15 and 16, the notches being beyond the pivot 11. 17 is a tempered resilient latch 60 detachably secured to the rear face of the fan casing 2 as by means of the screws 18 and having the bead 19 opposite to the pivot 11 for alternative engagement in the notches 65 15 and 16 for holding the handle in its substantially vertical and horizontal positions respectively. The portion of the face of the head 14 intermediate these notches is 70 slideable over the bead so that the intermediate 75 positions of the handle may be varied. The latch 17 has the free end 20 extending above the bead a sufficient distance so that it may be manually engaged to move the bead out of the notch which it engages. By reason 80 of this construction, the latch may be readily removed and replaced, and because of the increased leverage it is not necessary to have as strong a latch as in a construction where the lock is to the rear of the handle 85 pivot.

In order to make the handle of as light a weight as possible, the bifurcated end portion 10 is formed of some soft metal which is of light weight, such as aluminum, and 85 in order to avoid objectionable wear upon the head 14, the wear plate 21 is provided having a shape corresponding to that of the head with registering notches in its outer periphery. This wear plate preferably 90 forms the inner side of the head and is secured thereto when casting the bifurcated end portion. For more firmly holding the wear plate in place, it has the struck out 95 ears 22 embedded in the head.

What I claim as my invention is:

1. The combination with a vacuum cleaner having a motor casing and a fan casing, of a handle having a bifurcated end portion pivotally connected to said motor casing 100 near its forward end, one of said furcations being formed of soft metal, a wear plate secured to one side of said furcation at the lower end thereof and corresponding in shape thereto, said wear plate having 105 struck-out ears embedded in said furcation,

and a latch mounted on said fan casing engageable with notches in said wear plate for holding said handle in different positions of rotative adjustment relative to said motor 5 casing.

2. The combination with a vacuum cleaner having a motor casing and a fan casing projecting beyond said motor casing to form a shoulder, of a handle having an end portion 10 pivotally connected to said motor casing and a resilient one-piece latch rigidly secured directly to the rear face of the shoulder formed by the fan casing and extending upwardly along the rear face of said shoulder, a portion of said latch being engageable 15 with the end portion of said handle for holding the latter in a predetermined position of rotative adjustment relative to said motor casing.

20 3. The combination with a vacuum cleaner having a motor casing and a fan casing connected to one end thereof, said motor casing having a smaller diameter than said fan casing whereby the latter forms a shoulder, of a handle pivotally connected to said motor casing adjacent to said fan casing and having a portion projecting beyond the pivot, said projecting portion having a shoulder, and a latch member rigidly secured 25 directly to the rear face of the shoulder formed by said fan casing and having a projection intermediate its ends adapted to engage the shoulder upon the projecting portion of said handle to retain the latter in one position of rotative adjustment, the free end of said latch being adapted to be 30 manually engaged to disengage the projection from said shoulder.

4. The combination with a vacuum cleaner 40 having a motor casing and a fan casing secured to one end thereof, said motor casing having a smaller diameter than the fan casing whereby the latter forms a shoulder, of a handle having a bifurcated portion piv-

oted upon said motor casing, one furcation 45 having a portion projecting beyond its pivot, the free end of said projecting portion having spaced notches therein, and a substantially vertical yieldable latch rigidly secured directly to the rear face of the shoulder 50 formed by said fan casing and having a projection intermediate the ends adapted to alternately engage the notches in the projecting portion of said furcation for retaining said handle in different positions of rotative adjustment.

5. The combination with a portable appliance, of a handle having a portion constructed of relatively soft material, said portion being pivotally connected to said 60 appliance and having spaced notches formed in the end thereof beyond the pivot, means carried by said appliance adapted to alternately engage said notches to retain said handle in different positions of rotative adjustment, and a wear plate secured to one side of said portion and having notches 65 therein registering with the notches aforesaid for engagement by the retaining means whereby wear upon the portion constructed 70 of soft material is avoided.

6. The combination with a vacuum cleaner having a motor casing and a fan casing, of a handle having a portion constructed of relatively soft material, said portion being pivotally connected to said motor casing and having a notch formed therein beyond the pivot, means carried by said fan casing adapted to engage said notch to retain said handle in one position of rotative adjustment, and a wear plate secured to one side of said portion and having a notch therein 75 registering with the notch aforesaid for engagement by the retaining means whereby wear on the portion constructed of soft material is avoided.

In testimony whereof I affix my signature.
EGBERT R. FIELD.
